UNITED STATES PATENT OFFICE.

FREDRICK F. CLARK, OF ALAMEDA, CALIFORNIA, ASSIGNOR TO ALASKA PACKERS' ASSOCIATION, OF SAN FRANCISCO, CALIFORNIA, A CORPORATION OF CALIFORNIA.

FEED FOR SHEET-SLITTING MACHINES.

1,232,450.

Specification of Letters Patent. Patented July 3, 1917.

Application filed January 18, 1917. Serial No. 142,899.

To all whom it may concern:

Be it known that I, FREDRICK F. CLARK, a citizen of the United States, residing at Alameda, in the county of Alameda and State of California, have invented new and useful Improvements in Feed for Sheet-Slitting Machines, of which the following is a specification.

This invention relates to mechanism for feeding metallic sheets to slitters and like devices used in can making; and has for its object to simplify and improve the construction and operation of such devices.

Owing to the large size of the sheets fed to slitting machines, it is a difficult matter to feed them automatically, one at a time, from a stack of such, and the usual method is to feed them by hand. This is not only slow and cumbersome but results in the irregular placing of them in the slitters, with a consequent uneven cutting of the body blanks.

In the present invention I provide mechanism in the form of an adjustment for the usual slitting machine and comprising a hopper adjustable as to length and width and arranged to receive the sheets horizontally in piles, means for supporting the stack of sheets at the bottom spaced above the bed plate of the frame, reciprocating knife edge devices to separate the bottom sheet from the stack and move it from the hopper, means at the rear of the hopper to permit a single sheet to pass through, and guiding and advancing means to receive the sheets after they have left the hopper and move them to the slitting machine.

One form which my invention may assume is exemplified in the following description and illustrated in the accompanying drawings, in which—

Figure 1 shows a plan view of a device embodying my invention.

Fig. 2 shows a sectional view, taken on the line 2—2 of Fig. 1.

Fig. 3 shows a sectional view, taken on the line 3—3 of Fig. 1.

As herein shown, the feeding mechanism comprises a frame 10 having a bed-plate 11, upon which are fixed, at the outer ends toward the front thereof, two standards 12 adjustable toward and from each other and forming the ends of a hopper, in which is received the sheets 13 in a horizontal position, piled one above the other. Extending

longitudinally of the frame, above the bed-plate, is an angle bar 14, at the front and rear sides, upon each of which is carried a plurality of vertical bars 15 spaced apart and supported adjustably thereon each by means of a vertical set-screw 16, turnably mounted in the bent upper end of the bar and screw-threaded into the top flange of the adjacent angle bar 14.

A set screw 18, passing through a slot in the vertical flange of the angle bar, serves to support and guide the lower end of each bar 15. The lower ends of the bars 15, at the front side, have inwardly bent lower ends 19 forming a ledge to receive and support the front edges of the pile of sheets, while the bars 15, at the rear, are cut straight at their lower ends and beveled at the rear corners to form gage bars. The rear side of the pile is supported upon a plurality of idlers 20, each journaled in a holder 21 detachably secured to the bed-plate and with which the said gage bars co-operate to permit a single sheet only to pass from the hopper.

Slidably in fore and aft grooves 22, formed in the bed-plate, are two reciprocating bars 23, each provided with one or more spring-pressed dogs or pawls 24, to engage and advance the sheets after they have left the hopper. Transverse bars 25 rigidly connect the two reciprocating bars and upon them are fixed two, separating dogs 26 pivoted in a channel member 37, secured to the cross bars. Each separating dog has a tapered forward end and at its top carries a ledger plate 27 having an undercut front edge to engage and separate the lowermost sheet from the stack. A spring 28 yieldingly holds each dog in position to make the proper separation of a single sheet.

Adjacent to each channel bar 37 is an upwardly extending flange 29 secured to the cross bars 25 to assist in supporting the pile of sheets in proper position and prevent sagging thereof. At intervals on the bed-plate are supporting rollers 30, each journaled in a holder 31 detachably secured to the bed-plate, so that sheets which are of a large size are supported in the same plane at various points while at the same time friction is reduced.

At the rear of the hopper and in a position to receive the sheets as they emerge

therefrom is a pair of rollers 32, yieldingly mounted in blocks 33 fixed to the bed-plate and driven by suitable gearing 34. These rollers are in a position to receive the sheets between them and advance said sheets to a slitting machine, a part of which machine is shown at 35.

In operation, the hopper is filled with sheets which are supported above the bed-plate on the front carrying bars 15, rollers 20 and 30 and flanges 29. The gage bars 15 are adjusted relative to the rollers 20 to leave a space between sufficient to permit a single sheet only to pass from the hopper. 10 The reciprocating bars 23 and dogs 26 are actuated by suitable driving mechanism not shown. Upon each stroke of the reciprocating members the lowermost sheet in the stack is engaged and separated from the pile by the ledger plates 27, on the dogs, and moved thereby a distance sufficient to force the sheet into the rollers 32. Thereafter the reciprocating bars are retracted to engage with the next sheet and on the subsequent stroke the first sheet is engaged by the forwardly disposed dogs 24 and its advancement toward the slitting machine assisted thereby. 15

The mechanical and automatic feeding of large metallic sheets to a slitting machine in the manner described will double the capacity of the slitting machine as compared with hand feeding. Also the sheets when so fed are certain to be properly and evenly 20 presented to the slitting machine, with the result that the blanks for the cans are cut uniformly and squarely.

Various changes in the construction and arrangement of the several parts herein shown and described may be employed without departing from the spirit of my invention as disclosed in the appended claims. 25

Having thus described my invention, what I claim and desire to secure by Letters 30 Patent is—

1. In a sheet feeding mechanism, a hopper, a pair of reciprocating bars below the hopper having sheet advancing means, transverse bars connecting said reciprocating bars, members secured to the transverse bars and arranged transverse of the latter, sheet separating means connected to said members, members connected to the transverse bars and extending transversely thereof to assist 35 in supporting the stack of blanks, and means to actuate said reciprocating bars.

2. In a sheet feeding mechanism, a hopper, a pair of reciprocating bars below the hopper having sheet advancing means, a cross-support connecting said bars, and sheet separating means formed independent of and carried by the support and arranged 40 between the sheet advancing means.

3. In a sheet feeding mechanism, a hopper, a pair of reciprocating bars below the

hopper having sheet advancing means, a cross-support connecting said bars, sheet separating means carried by the support and arranged between the sheet advancing means, and supports for the stack of blanks 45 carried by said cross-support.

4. In a sheet feeding mechanism, a hopper, a reciprocating device beneath the hopper, a plurality of spaced stack supporters carried by said device, and sheet separators 50 carried by said device and arranged in the spaces between the stack supporters.

5. In a sheet feeding mechanism, a hopper, a reciprocating device including spaced side bars, a cross bar connecting said side bars, channeled members independent of the side bars and connected to the cross bar and arranged parallel to the side bars, and separating dogs pivoted in the channels of 55 said channel members.

6. In a sheet feeding mechanism, a hopper, a reciprocating device including spaced side bars, a cross bar connecting said side bars, channeled members connected to the cross bar and arranged parallel to the side 60 bars, separating dogs pivoted in the channels of said channeled members, and vertically arranged flanges adjacent the channeled members to support the stack and carried by the cross bar.

7. In a sheet feeding mechanism, a hopper having an outlet including a roller having its top arc forming the bottom of the outlet, and arranged to support the bottom of the stack within the hopper and at one side of the stack, a pair of coöperating superposed feed-out rollers having their confronting parts alined with the top arc of said roller, a carrier, means on the carrier to separate the sheets, spaced upwardly extending flanges on the carrier and movable therewith in advance of the separator means for supporting a separated sheet and for positively guiding and holding same over the hopper roller and between the feeding-out rollers, and means on the carrier in advance of the separator means and movable with the carrier to advance the sheets past the feeding-out rollers after the sheets have left the latter. 100

8. In a sheet feeding mechanism, a hopper having an outlet, including means arranged to support the bottom of the stack within the hopper and at one side of the stack, feeding-out rollers in front of the hopper arranged with their confronting parts in alinement with said stack supporting means, a carrier, means on the carrier to separate the sheets, means on the carrier movable therewith in advance of the separator means for supporting a separated sheet and for positively guiding and holding same over the hopper means and between the feeding-out rollers, and means movable with the carrier for advancing the 110

sheets after same have left the feeding-out rollers.

9. In a sheet feeding mechanism, a hopper having means for engaging the blank ends, 5 angle-bars having vertical webs confronting each other and tops extending outwardly, vertical bars engaged with the vertical web of one angle-bar and having their lower ends formed to support one side of the 10 stack, vertical gage bars engaged with the vertical web of the other angle-bar, means coöperating with the lower ends of the gage bars to form a hopper outlet, screws connected to the vertical bars and the tops of 15 the angle-bars to vertically adjust the ver-

tical bars, and means for clamping the vertical bars to the vertical webs of the angle-bars in all adjustments of the vertical bars, said last named means being accessible for manipulation from beneath the tops of the 20 angle-irons and to the rear of the vertical webs of the angle irons.

In testimony whereof I have hereunto set my hand in the presence of two subscribing witnesses.

FRED F. CLARK.
